(57) **CLAIM**

The ornamental design for a topical insect repellent container with surface ornamentation, as shown and described.

DESCRIPTION

The patent or application file contains at least one drawing executed in color. Copies of this patent or patent application publication with color drawing(s) will be provided by the Office upon request and payment of the necessary fee.

FIG. 1 is a perspective view of a topical insect repellent container with surface ornamentation embodying our new design;

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is bottom view thereof;

FIG. 8 is a perspective view of a second embodiment of a topical insect repellent container with surface ornamentation embodying our new design;

FIG. 9 is a front view thereof;

FIG. 10 is a rear view thereof;

FIG. 11 is a left side view thereof;

FIG. 12 is a right side view thereof;

FIG. 13 is a top view thereof;

FIG. 14 is bottom view thereof;

FIG. 15 is a perspective view of a third embodiment of a topical insect repellent container with surface ornamentation embodying our new design;

FIG. 16 is a front view thereof;

FIG. 17 is a rear view thereof;

FIG. 18 is a left side view thereof;

FIG. 19 is a right side view thereof;

FIG. 20 is a top view thereof;

FIG. 21 is bottom view thereof;

FIG. 22 is a perspective view of a fourth embodiment of a topical insect repellent container with surface ornamentation embodying our new design;

(Continued)

FIG. 23 is a front view thereof;
 FIG. 24 is a rear view thereof;
 FIG. 25 is a left side view thereof;
 FIG. 26 is a right side view thereof;
 FIG. 27 is a top view thereof; and
 FIG. 28 is bottom view thereof;
 FIG. 29 is a perspective view of a fifth embodiment of a topical insect repellent container with surface ornamentation embodying our new design;
 FIG. 30 is a front view thereof;
 FIG. 31 is a rear view thereof;
 FIG. 32 is a left side view thereof;
 FIG. 33 is a right side view thereof;
 FIG. 34 is a top view thereof; and
 FIG. 35 is bottom view thereof.
 FIG. 36 is a perspective view of a sixth embodiment of a topical insect repellent container with surface ornamentation embodying our new design;
 FIG. 37 is a front view thereof;
 FIG. 38 is a rear view thereof;
 FIG. 39 is a left side view thereof;
 FIG. 40 is a right side view thereof;
 FIG. 41 is a top view thereof; and
 FIG. 42 is bottom view thereof.
 The evenly broken lines are shown for the purpose of illustrating parts of the article that form no part of the claim. The dot-dash lines represent the boundaries of the claim and form no part thereof.
